UNITED STATES PATENT OFFICE

JOHN CLATWORTHY, OF TOTTENHAM HALE, LONDON, ENGLAND, ASSIGNOR TO
D. GESTETNER, LIMITED, OF LONDON, ENGLAND

SHEET-FEEDING MECHANISM AND DUPLICATING MACHINE PROVIDED WITH SUCH MECHANISM

Application filed November 14, 1925, Serial No. 69,036, and in Great Britain December 1, 1924.

This invention relates to sheet-feeding mechanism and particularly to the sheet-feeding mechanism of stencil and type duplicating machines in which a table is provided for the accommodation of a pile of sheets to be fed successively to, for instance, means whereby a stencil or other impression is formed thereon, and means are provided by which the table is raised into the position in which the first sheet may be delivered from the pile.

The invention also relates to duplicating machines provided with such mechanism.

According to one feature of the invention the sheet-feeding mechanism comprises means whereby the upward motion of the feed table, in the preliminary adjustment of its position, is positively arrested at the point when the table is in the position for the top sheet of the pile thereon to be fed.

The invention consists more particularly in sheet-feeding mechanism of the kind in which a trip bar, that is to say a bar having a projecting lip adapted to be brought to bear upon the surface of the paper to cause the feed-mechanism to buckle the sheet and to rotate, thus releasing the sheet of paper, is provided, and is characterized in this that the trip bar is associated with means whereby rotation of the trip bar under the action of the upward motion of the feed table in the preliminary adjustment of its position is prevented.

The rotation of the trip bar in accordance with the invention may, as in known constructions, be effected through the intermediary of a reciprocating bar to which motion is imparted by a cam associated with a spindle operated means adapted to push successive sheets of paper forward, thereby causing the top sheet to buckle and its edge to spring forward when released by the trip bar.

In one construction in accordance with the invention the trip bar is provided with a slotted cam engaging a pin on the aforesaid reciprocating bar in such a manner that the reciprocation of the bar will rotate the trip bar about its axis while upward pressure on the trip bar will cause the cam to bear against

the pin on the reciprocating bar and prevent rotational motion of the trip bar.

The invention further comprises the provision of means adapted positively to arrest the upward motion of the feed table when in the normal operation of the device the feed table has been raised to a predetermined height.

Preferably, a machine provided with means of the character defined in the preceding paragraph comprises also means adapted to return the table to its initial position after it has been fully raised.

Conveniently, in such case, the machine is also provided with means necessitating the intervention of the operator to enable the table to be again raised.

Conveniently also means are provided whereby after the table has been raised to the fullest extent the operation of the means adapted to feed forward the sheets from the pile supported on the table is interrupted.

Preferably, when the device is associated with a machine provided with a pressure roller or equivalent device adapted to force the sheet against an impression-forming or other device operating upon the sheet, means are provided for interrupting the functioning of the pressure roller.

Optionally, in accordance with the invention, means may be provided for interrupting the operation of the moving parts of the machine as a whole when the table has reached its maximum or highest position, and such means may comprise a device adapted to disconnect the machine from the source of power whereby its operation is effected.

Thus, in accordance with this feature of the invention, the return of the feed table to its initial position may be employed for operating a switch adapted to interrupt the supply of current to an electric motor employed as a source of power.

In one construction in accordance with the invention the switch in question is so located that the feed table or its supports in descending contact with and operate the movable element of the switch.

A further feature of the invention comprises the provision of improved means for

securing a parallel or horizontal rising motion of the feed table between its upper and lower limiting positions.

According to this feature of the invention 5 two arms are each pivotally connected with some fixed point on the machine on opposite sides thereof, the remote ends of these arms being connected by a bar or the like with which one end of the table is pivotally connected, and from these arms lugs project, the 10 ends of these lugs contacting directly or preferably through antifriction rollers with cams so formed as to move the arms about their pivots to an extent sufficient to lift the ends 15 of the arms and the bar connecting the said ends through a height sufficient to raise the outer end of the feed table to the same height as the inner end thereof is raised by two arms mounted coaxially with the cams and 20 conveniently on the same spindle.

As will be understood, the load upon the table will vary according to the amount of paper thereon and consequently a different effort would normally be needed for raising 25 the table.

A further feature of the invention consists in the provision of means for equalizing the effort in raising the table by hand into the initial feeding position whatever may be the 30 quantity of paper supported by the table.

Certain of the further features hereinafter referred to are solely concerned with devices in which ratchet mechanism is employed for the purpose in question, while others are of 35 more general application.

When ratchet mechanism is so used, it is not convenient to arrange a ratchet which shall be operated to elevate the table after each individual sheet of paper has been fed 40 forward and it will, of course, be clear that with different thicknesses of paper it would be necessary with a device so arranged to employ differently cut ratchets according to the thickness of the paper.

According to the invention, means whereby 45 the pawl is maintained out of contact with the teeth of the ratchet until a determined number of sheets has been fed forward is provided.

Conveniently the means in question is associated with the trip bar and in such case the means associated with the trip bar may co-operate with ancillary means adapted to maintain the pawl bar in an elevated position 55 during a portion of its stroke.

The means associated with the trip bar may, for example, be arranged to maintain the pawl bar in the raised position during one portion of its stroke, while the ancillary 60 support is arranged to maintain the pawl bar in the raised position during the remaining portion of its stroke until a determined number of sheets has been fed, when the two supporting means will assume relative positions 65 in which they permit the pawl bar to descend.

Thus, in accordance with the invention, an arm provided with a shoulder may be pivotally mounted in such position relative to the pawl bar that a bearing surface provided on the shoulder co-operates with a projection on the reciprocating pawl bar to retain it in a raised position during its reciprocation until the lip on the trip bar is permitted to descend in consequence of the feeding forward of a number of sheets of paper sufficient to necessitate the lifting of the table.

The reciprocation of the pawl bar is effected from some suitable moving element of the machine as, for instance, from the spindle operating the pusher mechanism, adapted to feed forward and buckle the sheets in the manner above indicated.

To this end a cam or eccentric may be provided upon this spindle operating upon a strap or arm engaging a pin provided on 85 the pawl bar.

As will be understood, a retaining pawl will be associated with the ratchet. This retaining pawl is conveniently associated with means whereby it may be raised from the ratchet and preferably also with means whereby the operating pawl may be similarly raised to permit the table to descend.

The retaining pawl is conveniently associated with a finger-piece and preferably the finger-piece is associated with means adapted to operate a clutch on the feed spindle in such manner that when the retaining pawl is released from the ratchet the clutch is likewise 95 released.

Conveniently, the ratchet is formed on the edge of a disc and is arranged to operate through reduction gear a spindle, the rotation of which effects the raising of the table.

Thus, for instance, the ratchet disc may be 105 associated with a pinion engaging a toothed sector secured to the spindle.

The employment of a ratchet in conjunction with reduction gear in this manner renders it possible to provide for a considerable 110 lift of the feed table and thus to provide a machine adapted to accommodate, for instance, a ream of paper.

The object of this is to prevent, owing to an oversight on the part of the operator, the 115 table, when unloaded, being raised to its highest point which would result in its being returned to its initial position.

The invention also comprises the provision of means whereby when the table is in its lowermost position operation of the lifting mechanism by the pawl bar is prevented in the absence of the intervention of the operator.

Thus, in accordance with the invention, 125 when a ratchet disc operated by a pawl is employed for raising the feed table, a portion of the disc may be left unprovided with teeth in such a position that when the table has dropped to its lowermost position the pawl 130

on the reciprocating pawl bar will simply bear upon this untoothed portion and move idly thereover.

From the foregoing description it will be gathered that when the table is in its lowermost position the lip of the trip bar will be permitted to descend and the cam thereon will in such case release the reciprocating pawl bar and will permit the pawl thereon to descend into contact with the ratchet wheel.

If, when in this position, the clutch on the feed mechanism is left in engagement, the pusher mechanism on the feed device will be operated and so also will be the reciprocating pawl bar and in the absence of some means adapted to prevent raising of the table from the initial position the table would, after it has descended, be again raised unless the operation of the machine had been interrupted.

20 A further feature of the invention comprises the provision of means adapted to prevent the feed pawl engaging with the ratchet when the table has been raised to the highest position.

25 To this end, on the ratchet disc an elevated portion may be provided adapted to prevent the pawl engaging with the teeth thereon.

A further, though optional, feature of the invention consists in the provision of means 30 adapted to interrupt the operation of the lifting mechanism when the table has been raised to a predetermined height in the normal operation of the machine.

35 Preferably such means also enables the table to return to its initial position.

Thus, in accordance with the invention, means adapted to raise the pawls from the ratchet forming part of the lifting mechanism when the table has been raised to a predetermined height may be provided.

40 In one construction in accordance with the invention the means adapted to raise the pawls may be pivoted on an axis coaxial with the axis of the ratchet wheel, while on the ratchet wheel a member may be formed adapted 45 to contact with the said means and to carry it round during the raising of the table until finally it engages a projection on the retaining pawl, raising the said pawl from the ratchet and simultaneously or subsequently raising the operating pawl.

45 With this arrangement, as will be understood, so soon as both pawls are raised the ratchet is free to move, under the action of gravity, in the reverse direction to that in which it is caused to move in the operation of raising the table.

Conveniently, the member which may be in 50 the form of a block on the side of the ratchet co-operating with the pawl-lifting means is so dimensioned that when the ratchet is rotated to the full extent and in the backward or reverse direction the said means is moved 55 into a position in which one of its faces con-

tacts with the member and disengages it from the retaining pawl.

A still further feature of the invention consists in the provision of means adapted to maintain a substantially constant pressure 70 upon the sheet after it has been released by the feeding mechanism and is being drawn forward by the impression-forming or other means operating thereon.

Thus, in accordance with this feature of 75 the invention as applied to a feeding mechanism of known character comprising fingers which are periodically retracted and depressed into contact with the paper, advanced to push the sheet forward and raised to release it, a roller or other pressure member 80 associated with a spring adapted to force the pressure member on the pile of sheets may be provided.

Conveniently, with this arrangement a 85 roller formed, for instance, of rubber or the like may be mounted on the frame carrying the fingers and at a point adjacent to where these fingers are pivotally connected with the frame.

In one construction in which the fingers are 90 pivotally connected with a frame which in turn is pivotally mounted in suitable fixed supports and is oscillated by a cam or eccentric mounted on a spindle on which a second cam operates to raise and lower the fingers from the top sheet of the pile, the roller 95 may be secured in a carriage pivotally mounted on the spindle, providing a connection between the fingers and the frame, a spring or springs being provided for pressing the roller against the upper surface of the pile of sheets.

The invention will be described further in detail and by way of example, as applied to a 100 duplicating machine of the kind in which the stencil secured to a flexible stencil carrier travels over a pair of inking cylinders, with reference to the accompanying drawings, in which:—

Figure 1 is a fragmentary view in elevation showing the mechanism located at one side of the feed table and with the table in the lowermost position, and

Figure 2 is a similar view showing the position of the several parts when the table is in its highest position, while

Figure 3 is a view in elevation showing the mechanism located at the other side of the feed table, with the latter in the lowermost position, and

Figure 4 is a corresponding view with the feed table raised and the trip bar in the position which it assumes to release a sheet of paper.

Figure 5 is a fragmentary view on a larger scale showing in particular the driving connection for the feed mechanism while,

Figure 6 is a fragmentary view on an enlarged scale showing certain elements of the

mechanism controlling the raising of the feed table and for interrupting the feed mechanism when the table has been raised to its highest position.

5 Figures 7, 7^b, 7^c and 7^d and Figures 8, 8^b, 8^c and 8^d are views showing certain elements of the mechanism for raising the table in the relative positions they will assume during the operation of the machine.

10 In the drawings, 1 is the trip bar provided with a projecting lip 2 adapted to be brought to bear on the surface of the paper to enable the feed mechanism to buckle the sheet and by its oscillation to release the buckled sheet the 15 edge of which will spring forward and be engaged between the pressure roller 3 mounted on the frame 4. The cam 8 is mounted on the spindle 10 driven by the toothed wheels 10^a, 10^b, and 10^c, the latter of which is secured on 20 the same shaft as the roller 5 and this shaft being rotated by hand or by an electric motor and operating also in known manner through the eccentric 10^d and the connecting rod 10^e, the frame 11 to which are secured the 25 fingers 12 carrying the rubber friction pads 13. The motion imparted to the frame 11 causes the fingers to be periodically retracted and raised from the pile of sheets to be fed and depressed into contact with the topmost sheet 30 of the pile when as they are advanced they cause the sheet to buckle with the result that the fore edge of the sheet will spring forward when released by the lip 2 of the trip bar, the 35 fingers being thereafter raised to release the sheet and then retracted. These fingers are pivotally connected with the frame which in turn is pivotally mounted at 14 on the side members of the machine. To the frame in question is secured a carriage 15 pivotally 40 mounted at 16 on the frame and in this carriage a roller 17 is secured, a spring 18 being provided for pressing the roller against the upper surface of the pile of sheets. This arrangement constitutes means adapted to 45 maintain substantially constant pressure on the sheet which is being fed after it has been released by the feeding mechanism and is being drawn forward by the impression-forming or other means operating thereon.

50 On the trip bar is a slotted cam 19 engaging a pin 20 on the reciprocating bar in such manner that the reciprocation of the bar will rotate the trip bar about its axis while upward pressure on the trip bar will cause 55 the slotted cam to bear against the pin which will in such case prevent rotational motion of the trip bar as the result of such upward pressure. In this way, as will be seen, the rotation of the trip bar about its axis will be 60 secured as the result of the operation of the feeding mechanism but lifting of the trip bar in consequence of pressure applied to it will be prevented.

For raising the feed table 20^b, which is 65 provided with a sheet metal extension 20^c

forming part thereof and the forward portion of the support for the pile of sheets, in the construction illustrated, a ratchet mechanism is employed. This ratchet mechanism comprises a ratchet wheel 21 which is operated upon by a pawl 22 provided on the reciprocating pawl bar 23 which is furnished with a slot 24 engaging a pin 25 on the frame of the machine.

This bar is reciprocated through the intermediary of the eccentric strap 26 which is provided with a slot 26^a engaging a pin 26^b secured to an adjacent portion of the machine frame, such reciprocation being secured by the motion of the eccentric 27. An arm 28 pivotally mounted about the axis of the screw 29 is connected by a spring 30 to a fixed point on the machine, the spring operating to constrain the arm to move against the stop 31. On this arm a shoulder 32 is provided. This shoulder forms a bearing surface for the reciprocating pawl bar and assists in retaining it in a raised position during its reciprocation until the lip 2 on the trip bar is permitted to descend in consequence of the feeding forward of a number of sheets of paper sufficient to necessitate the lifting of the table. This cycle of operations of the pawl bar 23 and the manner in which its descent to enable the pawl to engage the ratchet during its forward stroke, is prevented by the cam on the trip bar until a given number of sheets has been fed and the lip of the trip bar has in consequence been allowed to descend a predetermined amount, is shown more clearly in Figures 7, 7^b, 7^c, and 7^d which illustrate the several positions assumed by the elements above described in the operation of the machine. In Figure 7, as will be seen, the pawl bar 23 is in its extreme retracted position the pawl 22 being maintained out of engagement with the ratchet 21 owing to the forward end of the pawl bar being supported on the cam 33 mounted on the trip bar 1, the lip 2 of the trip bar being prevented from descending by the height of the pile of sheets supported on the feed table. From its extreme retracted position during the feeding of the sheets and before the trip bar is rotated to release the fore edge of the topmost sheet the pawl bar will be supported by the projection or shoulder 32 on the arm 28 as shown in Figure 7^b. As the trip bar rotates the cam 33 will engage against the fore end of the pawl bar lifting it from the shoulder 32, as shown in Figure 7^c, and subsequently as the trip bar continues its motion allowing it to descend into the position shown in Figure 7^d into contact with the ratchet 21 but in this position the pawl bar being in its extreme forward position the ratchet will not be actuated and it will be released from the ratchet re-assuming the position shown in Figure 7 as the trip bar makes its return movement to bring its lip 2 into contact with the pile of 130

sheets or being again released, as shown in Figure 8, if the height of the pile of sheets is such as to render necessary the raising of the feed table. In this case the succeeding reciprocation of the pawl bar into the position indicated in Figure 8^b will cause the ratchet, owing to the continued engagement with it of the pawl, to be moved thereby raising the feed table. The cam 33 on the trip bar, as shown in Figure 8^c then operates to raise the pawl bar, and finally allowing it to assume the position shown in Figure 8^d or, in other words, the same position as is illustrated by Figure 7^d and assuming that the table has been sufficiently raised by the above described movements of the ratchet the next position assumed by the several parts will be as shown in Figure 7, when the next cycle of operations will be as indicated in Figure 7^b, 7^c, and 7^d.

If the table has not been sufficiently raised the cycle will, on the other hand, be as illustrated in Figures 8^b, 8^c, and 8^d.

A retaining pawl 36 is associated with the ratchet. This pawl is provided on a lever 37 pivoted on the screw 38, a finger-piece 39 being provided on the lever adapted to enable the retaining pawl to be raised from the ratchet should the operator desire to cause the feed table to descend in order that more paper may be placed in position thereon. On the pivoted lever a lifter 40 is provided. This lifter is adapted to contact with the reciprocating pawl bar so that pressure upon the finger-piece not only raises the retaining pawl 36 but also the operating pawl from the ratchet wheel.

Further, the lever in question operates through the pin 41 on the lever 42 pivoted about the centre 43 and connected by the pin 44 with the bell crank lever 45 pivoted at 46. Pressure upon the finger-piece moves the same from the dotted position into the position shown in full lines in Figures 1 and 2 and such motion causes the bell crank lever to engage a pin 47, thereby releasing the clutch 48 provided on the feed spindle. In this way the operation of the feed spindle and thus of the feed mechanism is interrupted simultaneously with the interruption of the motion 50 of the lifting mechanism.

The teeth of the ratchet, as will be seen from the drawings, are formed on the edge of a disc and with the disc is associated a toothed wheel 49 operating through the pinion 50 upon the toothed sector 51 which is secured to the spindle 52 which in turn operates upon the table.

The employment of a ratchet in conjunction with reduction gear in this manner renders it possible to provide for a considerable lift of the feed table and thus to provide a machine adapted to accommodate, for instance, a ream of paper.

The ratchet wheel in the construction described is provided with a portion in which

no teeth are formed and consequently when the feed table has dropped to its lowermost position the pawl on the reciprocating pawl bar will simply bear on this untoothed portion and will oscillate idly thereover even though the clutch on the feed spindle has not been disengaged.

From the above it will be gathered that when the table is in its lowermost position the lip of the trip bar will be permitted to descend and the cam thereon will in such case release the reciprocating pawl bar and will permit the pawl on the said pawl bar to descend into contact with the ratchet wheel.

To prevent the pawl bar engaging with the ratchet when the table has been raised to the highest position and thus operating thereon and straining the mechanism, an elevation 53 is provided thereon and in the construction illustrated means are provided adapted to interrupt the operation of the lifting mechanism when the table has been raised to a predetermined height in the normal operation of the machine and to return the table into its initial position.

For this purpose means are provided adapted to raise the pawls from the ratchet forming part of the lifting mechanism when the table has been raised to a predetermined height.

Such means comprises a member 54 pivoted about the same axis the ratchet wheel and on the side of the ratchet wheel the member 55 is provided adapted to contact with the aforesaid member and to carry it around during the raising of the table until finally it engages a projection on the retaining pawl, thereby raising the said pawl from the ratchet and simultaneously raising the operating pawl.

So soon as these pawls have been raised and the ratchet freed, the ratchet will move in the reverse direction to that in which it is caused to move in the operation of raising the table.

This motion of the ratchet which, as will be understood, is effected through the operation of gravity upon the feed table, brings the member 55 into such position that it strikes the member 54, as shown in Figure 1, and thus moves the said member out of the position in which it operates upon the retaining pawl and in the figure in question it is shown in the operation of releasing the same.

The member 54 then falls back into the position shown in dotted line in Figure 1.

The descent of the table may be arranged to interrupt the operation of the machine as a whole.

For this purpose where the machine is driven electrically a switch 56, see Figures 3 and 4, may be provided on the base-board, the switch comprising a movable element 57 adapted to be struck by the table or one of

the arms supporting it in the downward motion of the table.

Conveniently, the table is arranged to be maintained in a horizontal position during the raising and lowering operations.

5. This is effected in the constructions illustrated by providing two arms 58 which are pivotally connected at 59 with a fixed point on opposite sides of the machine frame, the remote ends of these arms being connected by 10 a bar 60; from these arms lugs 61 project, the ends of these lugs contacting through antifriction rollers 62 with cams 63 so formed as to move the arms about their pivots to an 15 extent sufficient to lift the ends of the arms and the bar connecting said ends sufficient to raise the rear end of the table to a height equal to that which the two arms 64 mounted coaxially with the cams will operate to raise 20 the fore end of the table.

25. The ends of these arms are provided with rollers 65 bearing upon the rear face of the feed board or table while adjacent to the remote end thereof and on its rear face a member 66 provided with a slot 67 is secured, said slot in which is engaged the bar connecting the remote ends of the arms operating to lift the rear end of the table. The form of 30 this slot is so chosen that in operation the arms cause the edge of the table adjacent to the forward edge or side of the pile of paper which is to be fed to press against a guard plate 68, which acts merely to keep the fore edge of the sheets in alignment one above the 35 other, thereby reducing any tendency of the pile of sheets to be retracted from the guard plate by the operation of the means feeding forward the individual sheets.

40. For equalizing the effort in raising the table by hand, a hand lever of the first order is employed, the arm of the lever 69 on one side of its fulcrum (see Figures 3 and 4) which is coaxial with the point 59 providing a sliding or rolling surface 70 for a pin 71 formed on 45 an arm 72 rigidly connected with the spindle which is operated from the feeding device in raising the table. With this arrangement the point of contact between the pin in question and the arm and the lever moves outward to 50 toward the end thereof from the point at which the table is in its lowest position to the point at which the table is in its highest position. For limiting motion of the lever a pin 73 is provided, while for constraining the lever to return into its initial position a spring 74, one end of which is connected with the lever 55 as shown and the other end of which is connected to a fixed point on the machine, is provided.

60. As will be understood certain of the features above defined may be employed independently of other features; they may also be employed together in various combinations and the employment of the features individually or in any convenient or desirable

combination falls within the scope of the present application.

65. The invention is, as above indicated, concerned particularly with the sheet-feeding mechanism of type and stencil duplicating machines and is principally concerned with stencil duplicating machines of the type in which a stencil mounted in contact with a flexible carrier is caused to travel over a plurality of inking rollers.

70. The invention moreover extends to impression-producing machines and particularly duplicating machines provided with sheet-feeding mechanism comprising the features above specified or certain of them.

75. Finally it may be mentioned that the expression "duplicating machine" as used herein is intended to mean or include machines for use in duplicating documents, manuscript, typescript and other matter upon paper or the like by means, for instance, of stencils of the kind including a porous support such as yoshino paper and an ink or pigment-resisting coating in which openings corresponding with the matter to be reproduced are formed.

80. Having now described my invention, what I claim as new and desire to secure by Letters Patent is:—

85. 1. Sheet-feeding mechanism of the kind including a table, for the accommodation of a pile of sheets to be fed in succession and means for periodically raising the table during the normal operation of the mechanism, said mechanism comprising a trip bar, a projecting lip on said bar adapted to be brought to bear on the surface of the paper to cause the feed mechanism to buckle the sheet and is rotated periodically in order to release the sheet, the fore-edge thereof being thereby permitted to spring forward, and means associated with the trip bar adapted to inhibit the same from rotation under the action of pressure applied to it by raising the table and thereby positively to arrest the upward motion of the feed table in the preliminary adjustment of its height to bring the topmost sheet of the pile of sheets into position to be fed.

90. 2. Sheet-feeding mechanism of the kind including a table, for the accommodation of a pile of sheets to be fed in succession and means for periodically raising the table during the normal operation of the mechanism, said mechanism comprising a trip bar, a projecting lip on said trip bar adapted to be brought to bear on the surface of the paper to cause the feed mechanism to buckle the sheet and is rotated periodically in order to release the sheet, the fore-edge thereof being thereby permitted to spring forward, means adapted to push successive sheets forward, thereby causing the top sheet of a pile of sheets to buckle and its edge to spring forward when released by the trip bar, a spindle operating said means, a cam on said spindle,

5 a member adapted to be reciprocated by the cam, a connection between the member and the trip bar adapted to oscillate the latter, and means associated with the trip bar adapted to inhibit the same from rotation under the action of pressure applied to it by raising the table and thereby positively to arrest the upward motion of the feed table in the preliminary adjustment of its height to bring 10 the topmost sheet of the pile of sheets into position to be fed.

3. Sheet-feeding mechanism of the kind including a table, for the accommodation of a pile of sheets to be fed in succession and means 15 for periodically raising the table during the normal operation of the mechanism, said mechanism comprising a trip bar, means adapted to push successive sheets of paper forward, thereby causing the top sheet of a 20 pile of sheets supported on the table to buckle and its edge to spring forward when released by the trip bar, a spindle operating said means, a cam on said spindle, a member adapted to be reciprocated by the cam, a pin 25 on said member and a slotted cam on the trip bar engaging the pin, said slotted cam being adapted to rotate the trip bar about its axis when the member actuated by the cam is reciprocated and to prevent upward pressure 30 on the trip bar from causing the trip bar to rotate.

4. Sheet-feeding mechanism of the kind including a table, for the accommodation of a pile of sheets to be fed in succession and means 35 for periodically raising the table during the normal operation of the mechanism, said mechanism comprising a trip bar, means adapted to push successive sheets of paper forward, thereby causing the top sheet of a 40 pile of sheets supported on the table to buckle and its edge to spring forward when released by the trip bar, a spindle operating said means, a cam on said spindle, a member adapted to be reciprocated by the cam, a pin 45 on said member, a slotted cam on the trip bar engaging the pin, said slotted cam being adapted to rotate the trip bar about its axis when the member actuated by the cam is reciprocated and to prevent upward pressure 50 on the trip bar from causing the trip bar to rotate, and means for preventing the operation of the moving parts of the machine as a whole when the table has reached its highest position.

5. Sheet-feeding mechanism of the kind including a table, for the accommodation of a pile of sheets to be fed in succession and means for periodically raising the table during the normal operation of the mechanism, 55 said mechanism comprising a trip bar, means adapted to push successive sheets of paper forward, thereby causing the top sheet of a pile of sheets supported on the table to buckle and its edge to spring forward when released 60 by the trip bar, a spindle operating said

means, a cam on said spindle, a member adapted to be reciprocated by the cam, a pin on said member, a slotted cam on the trip bar engaging the pin, said slotted cam being adapted to rotate the trip bar about its axis when the member actuated by the cam is reciprocated and to prevent upward pressure on the trip bar, causing the trip bar to rotate, means for preventing the operation of the moving parts of the machine as a whole when the table has reached its highest position, and means whereby the return of the feed table to its initial position is employed for operating a switch adapted to interrupt the supply of current to an electric motor employed as 70 a source of power.

6. Sheet-feeding mechanism, as claimed in claim 5, having ratchet and pawl mechanism for raising the feed table, in which, for maintaining the pawl out of contact with the teeth of the ratchet until a predetermined number of sheets has been fed forward, with the trip bar is associated means adapted to maintain the pawl out of contact with the ratchet during a portion of its stroke and ancillary means are provided adapted to maintain the pawl out of contact with the teeth of the ratchet during the remaining portion of its stroke until the determined 80 number of sheets has been fed.

In testimony whereof I have signed my name to this specification.

JOHN CLATWORTHY.
